UNITED STATES PATENT OFFICE.

CHARLES T. DAVIS, OF NEW YORK, N. Y.

SURGICAL SUTURE.

1,382,715.

Specification of Letters Patent. Patented June 28, 1921.

Application filed March 17, 1920. Serial No. 366,570.

To all whom it may concern:

Be it known that I, CHARLES T. DAVIS, a citizen of the United States, and resident of New York city, in the county of Kings and 5 State of New York, have invented certain new and useful Improvements in Surgical Sutures, of which the following is a specification.

My invention relates to surgery and is especially directed to improvements in surgical ligatures or sutures.

Standard surgical sutures are manufactured in a great variety of materials and sizes generally packaged in sealed glass 15 tubes each containing a coiled suture immersed in a preserving or storing fluid. Each tube ordinarily carries a label of some kind for identifying the kind, size, absorption time or other characteristics of the particular suture therein, permitting the surgeon to select sutures adapted to the particular operation which is contemplated. In order to facilitate sterilization of the suture tubes by boiling, the labels are frequently placed within the tubes, where they 20 are more or less hard to read, rendering mistakes possible. Furthermore, in the operating room it is common practice to have an assistant remove the suture from its tube, 25 thread it through a needle and hand it to the surgeon at the proper moment; and when this procedure is followed, it is impossible for the surgeon to be certain that the correct suture is presented to him, so he 30 must rely entirely upon the care of his assistant. Mistakes in the selection of proper sutures are particularly likely to occur as 35 between sutures having different absorption periods. Such sutures are substantially 40 identical in appearance, the label affording the only reliable identification thereof; and the danger of employing a suture of short absorption periods in place of one having a long period will be readily appreciated.

One of the two main objects of my invention is to eliminate the danger of such mistakes by providing means for identifying each type of suture directly by imparting to it a characteristic color. This object includes the employment of a suitable color 50 scale or scheme comprising a series of distinctive colors, each of which is applied to and identifies a suture having certain characteristics as to material, size, absorption 55 period, or other qualities, according to a prearranged scheme. With such an ar-

angement, the nature of each suture can be ascertained at a glance by its color regardless of any label, and after the suture has been withdrawn from its container.

A further object is to provide a series of dyes adapted to impart to the sutures the desired characteristic colors, and which will be free from harmful effect both upon the sutures and upon the tissues with which 65 they come in contact during use.

I also provide a series of characteristically dyed sutures which can be sterilized by heat and otherwise treated in the usual way without materially affecting either the dye or the 70 suture.

As has been noted, it is customary to keep sutures immersed in a preserving fluid until they are needed for use. One object of this phase of my invention is to provide a 75 series of characteristically dyed sutures which may be immersed in the usual preserving fluids without affecting the dyes, sutures or fluid, the dyes preferably being insoluble in such fluids.

Another feature of my invention is the provision of a convenient package for surgical sutures which are characteristically dyed, the package bearing a legend serving as a guide to the characteristics of the 80 sutures identified by the various distinctive colors.

Ordinary uncolored sutures have a relatively light color ranging from a light yellowish brown to white, many being also 85 translucent. This natural coloring renders the sutures difficult to discern against the tissues through which they are passed in sewing a wound, necessitating the use of a much larger suture than is required by 90 the strain to which the suture will be subjected. One object of this phase of my invention is to provide sutures characteristically colored which will be easily discernible 95 against the tissues, permitting the employment of fine sutures and diminishing the size of the suture track, thus reducing 100 injury to the tissues of the body.

Another difficulty encountered in the employment of the usual sutures is the danger of carrying infection into the wound with the suture. While the greatest care is taken to sterilize sutures, they are quite likely in actual use to carry bacteria into the suture track from the skin of the patient or other infected areas through which 110 they pass. Furthermore, while the need for

absolute sterility of all objects and materials employed in connection with operations is universally recognized, yet the exigencies and emergencies of an operation are 5 likely to disturb the carefully planned routine, especially when a substantial part thereof is performed by assistants and nurses, who may be forgetful or confused. Consequently, it has been found that the 10 employment of sutures which are sterile when taken from their tubes is insufficient to prevent infection of the suture track, owing to the danger of contamination thereof by careless handling after removal, or from infected parts of the subject.

It has been sought heretofore to avoid this difficulty by impregnating sutures with iodin, which is intended to act as an antiseptic to prevent infection from the suture. 15 This practice, however, is open to several objections. In the first place, the germicidal effect of iodin has been overestimated, experiments showing that in three to four hours after using an iodin-impregnated 20 suture the iodin has entirely disappeared both from the suture and from the surrounding tissue. Furthermore, iodin is irritating and injurious to certain patients under all conditions, and decomposes under the 25 action of light and heat, causing deterioration of the suture materials, as well as giving rise to the formation of substances which are irritating to the tissues. This characteristic of iodin prevents the sterilization of 30 sutures impregnated therewith by application of heat, as by boiling, as such treatment completely destroys the tensile strength of 35 the suture. Consequently, the usual operating technic must be altered as respects sterilization when iodin impregnated sutures are 40 employed. Even without the application of heat, it has been found that iodin tends to weaken sutures to which it is applied.

The second principal object of my invention, therefore, is to avoid these difficulties by providing a suture which is colored with an antiseptic substance, as by impregnating it with an antiseptic dye. With this phase of my invention, the dye may also be used 45 for the additional purpose of imparting a color which will permit the suture to be readily discerned against the tissues. The employment of finer sutures rendered possible by this means not only reduces the 50 necessary laceration of tissues incident to sewing or suturing them, but also permits much more rapid sewing, a point of major importance in operating. Furthermore, the 55 cicatrice is substantially reduced, a result 60 which is greatly desired by patients.

A further object is to provide such an antiseptic dye which will have no harmful effect on the suture or its preserving fluid, and which can be heated in the 65 usual sterilizing process without affecting

the suture. I also preferably employ an antiseptic having much greater persistence and strength than iodin and which in its preferred form is adapted to penetrate the tissues much more readily, insuring sterility 70 both in and around the suture track.

My invention comprises the diminution or elimination of the difficulties above set forth, and the attainment of the objects outlined, by the application of coal-tar dyes and their derivatives to sutures. I have ascertained that dyes of this kind have no harmful effect whatever upon suture or ligature filament made of the various kinds of material generally employed therefor, such as catgut, 80 kangaroo tendons, silkworm gut, horse hair, silk, thread and similar substances. Such dyes do not weaken sutures to which they are applied, but in some cases have a strengthening effect thereon. Furthermore, 85 they are unaffected by moderate heat or light, permitting the sutures to be sterilized by heat in the usual way; and moreover, such coal-tar dyes have no effect on the usual storing fluids, being insoluble in such fluids 90 as toluol and xylol. Coal-tar dyes afford an almost unlimited range of colors, including many distinctive dark shades particularly suitable for rendering sutures conspicuous 95 against the tissues in which they are embedded. Moreover, certain coal-tar dyes are highly antiseptic, being much more powerful and persistent than iodin, while lacking the undesirable features of that element as indicated.

It has been found by experiment that coal-tar dyes from all of the well-recognized groups of such dyes are suitable for use in coloring sutures. Examples of such dyes are those generally known as Martius yellow, 100 crystal-violet 6 B, rhodamin B, acriflavin, methylene blue, scarlet 4 R, acid yellow A. T., fast green, orange R. R., indigo carmine, mercurochrome-220, thioflavin, nigrosin and phosphene. Furthermore, a large 105 number of such dyes are readily soluble in water, and when suture materials are soaked in water solutions of such dyes, they readily take the dye, and do not give it up in such storing fluids as toluol or xylol. Coal-tar 110 dyes may be applied to suture materials by this or any other well-known method, and where the antiseptic or germicidal action of the dye is not a primary requisite, any 115 standard chemical mordant, such as a watery 120 solution of tannin, may be used.

In attaining my first object, that of identifying each suture, by applying thereto a coal-tar dye of a characteristic color, it will be apparent that the sutures may be 125 classified in various ways on the basis of one or a combination of their different characteristics, such as material, size, or absorption period. According to my invention, a distinctive coal-tar dye is applied to each 130

separately classified suture, the wide color range of such dyes permitting an extensive classification if desired, without undue similarity of colors. Furthermore, the dyes may 5 be arranged systematically as to color, in accordance with the suture classification employed, providing what may be termed a chromatic scale, and facilitating ready identification of a relatively large number 10 of suture classes.

A convenient method of arranging the characteristically colored sutures and a suitable package therefor is illustrated in the accompanying drawings, in which:

15 Figure 1 is a front view, parts being broken away, and

Fig. 2 is a transverse sectional view.

The package shown in the drawings is constructed in accordance with the disclosure 20 of my Patent 1,121,232, and includes in general an outer container or box 11 preferably of the telescoping type, and a suitable socket forming member therein, such as the corrugated board insert 12. Each suture 13 shown in the form of a coiled filament is packaged in the usual sealed glass tube 14, which fits into a socket in member 12, the container being adapted to hold a 25 number of tubes 14. Each of the sutures 13 is dyed a characteristic color, it being immaterial whether all the sutures in a package are of the same color, or whether each package contains sutures of different colors. If desired, each tube may carry a label 30 either inside or outside of the tube, bearing suitable information regarding the nature 35 of the suture.

Upon the container 11, and preferably 40 upon a label on the outside thereof, may be mounted a suitable legend designating the suture characteristics indicated by each color. Various forms of legend may obviously be employed, including mere printed tabulation or recital of each color and the suture characteristics corresponding thereto. 45 If desired, however, the portion of the legend relating to each color may be printed in such color, or a suitable area of such color may be placed in juxtaposition to the printed legend to indicate graphically the color of the suture having the indicated 50 characteristics, this arrangement being particularly advantageous where a relatively large number of colors is employed, thus avoiding any ambiguity in the descriptive 55 terms applied to similar colors.

An example of a legend of this type which may be called a chromatic scale, is shown in Fig. 1, in which a series of consecutively arranged suitably colored areas 60 are each placed in juxtaposition to printed indicia which may include a description of the color 17, and should include a statement of the suture characteristics 18, the examples given, relating to catgut sutures of various absorption periods. It is obvious,

however, that a great many variations in the type of legend are possible, and the specific showing is primarily illustrative.

It will also be obvious that the package includes essentially a series of characteristically colored sutures and a suitable legend indicating the color scheme, and that these features may be embodied in a very large variety of packages, both as to the inner suture containers 14, the outer container 11, 70 and the type of legend; consequently I do not limit myself to the type of package illustrated.

A large number of variations in the arrangement of colors is obviously possible, 80 and my invention is not limited to any specific system of employing the colors to identify specified types of suture. Nor is my invention limited to the use of such a color scale to indicate variations in all of 85 the properties of sutures, as such scale may be limited to some one feature of the sutures, such as their absorption period or their material. For instance, plain catgut might be stained yellow, as with acriflavin; 10-day 90 chromic catgut could be stained green, as with brilliant green; 20-day chromic catgut, black, as with nigrosin; and 40-day chromic catgut, violet, as with crystal violet 6 B. Even with such a limited application 95 of my invention, the ever-present danger of mistakes in the absorption period of the suture employed at the operating table would be eliminated, as each type would be distinguished at a glance by the surgeon, 100 even after it had been removed from its original tube and label.

I also attain my second object, that of rendering sutures antiseptic, by impregnating such sutures with coal-tar dyes. Scientific investigation has established the fact that many coal-tar dyes possess distinct germicidal properties, certain of these dyes having a very powerful antiseptic effect. Some of the better known examples of this 110 type are mercurochrome-220, gentian violet, crystal violet and brilliant green, together with dyes of the acridine group generally known commercially as flavin antiseptics.

Antiseptic dyes of this character possess, 115 in common with the other coal-tar dyes, the above outlined advantages of ready application to standard suture materials and the absence of any harmful effect thereon. Moreover, they are free from the objections 120 to iodin above noted. In addition to such advantages, these dyes possess antiseptic properties, rendering them peculiarly adapted for use in sutures. For instance, they are especially effective in penetrating the 125 tissues about the suture track, producing asepsis throughout a relatively extensive region, this quality being especially strong in the acid dyes. Furthermore, many of these antiseptic dyes are soluble in water, 130

not only facilitating their application to 65 sutures and preventing their dissipation in the usual storing fluids, but also enabling them to permeate the tissues of the body in
5 which the suture is embedded by diffusion through the water which normally permeates such tissues. Moreover, while such antiseptic dyes are not irritating to the tissues of the body and are not poisonous when used as
10 indicated herein, certain of these dyes, such as acriflavin, proflavin, mercurochrome-220, gentian violet, etc. are more effective antiseptics than iodin, even when employed in very high dilutions.
15 A further advantage common to coal-tar dyes is the fact that mercury or iodin atoms may be substituted for certain of the atoms in each of such dyes, producing what are known as mercury and iodin substitution
20 products of the coal-tar dyes. It has been found that these substitution products possess distinct antiseptic qualities while retaining the advantages for use in sutures which have been hereinbefore outlined.
25 While iodin is objectionable in its free state as a germicide for sutures, it has been found that the objections thereto do not apply to the iodin substitution products of the coal-tar dyes, but that such substitution products
30 possess a greatly increased antiseptic effect. The mercury substitution products also have marked germicidal properties, which have been particularly investigated and demonstrated in connection with derivatives of the
35 fluoresceine group, one example being mercurochrome-220.

The methods of applying the coal-tar dyes to substances which are to be dyed therewith are well-known, and any of such methods
40 may be employed in applying the dyes to the suture material. Furthermore, any amount of dye which will be taken up by such material may be employed, though I have found that a relatively small quantity
45 is sufficient to produce both the coloring effect and to possess the desired germicidal strength. One method which may be used includes the soaking of suture material in a watery solution of the dye, which preferably
50 does not exceed 1% in concentration, it being understood that other solvents, such as weak soda solutions among others, may be employed, the proper solvents for the various dyes being well-known to those skilled in
55 the art. When the suture materials are thoroughly impregnated with the dye, they are taken out of the solution, and any surplus dye removed as by quick washing. If a watery solution has been employed, the
60 water remaining in the suture material is removed by any suitable dehydration process, such as the application of heat. The dyed suture is then coiled, placed in a glass tube, a suitable storing fluid, such as toluol or

xylol, is added, and the tubes are sealed and sterilized in the usual way. However, it will be understood that my invention is not limited to this specific form of packaging the individual suture.

As the physical and chemical characteristics of the coal-tar dyes have been exhaustively investigated and are well-known to those skilled in the art, I have not considered it necessary to indicate the various dyes which possess certain of such characteristics set forth in this specification, such as solubility in water or other specific fluids. It is also to be understood that, while I have mentioned certain dyes as possessing an especial antiseptic value, my invention is not limited to such dyes, to other dyes of the same general nature, nor even to dyes or their derivatives which at present are known to possess germicidal properties; since my invention does not consist in the discovery that certain dyes do or do not possess such properties, but in one phase thereof consists in the employment of such germicidal coal-tar dyes and their derivatives to render sutures antiseptic. As I am fully aware that many coal-tar dyes are suitable for use in sutures without impairing the efficacy of the sutures or interfering with the normal handling thereof, and as the determination of the germicidal effect of any dye does not require invention but merely the application of well-known scientific methods, I consider my invention to include the employment in sutures of any coal-tar dye which may by future investigation be identified as having antiseptic properties.

While I have mentioned the substitution of mercury and iodin in the coal-tar dyes, it will be apparent that other chemical elements or groups of elements, such as other halogens, other metals, or other chemical radicals, may be employed instead of iodin, and that other substitution products are known to possess germicidal value. Consequently, my invention is not limited to substitution products including iodin or mercury, but includes such other derivatives or products of this nature as are ascertained to have antiseptic value.

Coal-tar dyes have been divided into a number of classes each comprising derivatives and variations from a parent dye which usually gives its name to the class. Furthermore, substitution products in the different classes are well recognized. Consequently, I prefer to employ in the claims the term "coal-tar dyes" as embracing not only the parent dye of each class, but the derivatives and substitution products thereof, as set forth herein.

It will be understood that while I have used the term suture, as covering broadly the class of sewing or binding filaments

employed in surgery, my invention is equally applicable to the suture materials prior to manufacture thereof into sutures.

I claim:

- 5 1. The combination of a surgical suture and a coal tar preparation rendering the same antiseptic and dyeing the same a defining color.
- 10 2. A filament and a coal tar dye impregnating the same and forming a colored surgical suture having antiseptic qualities.
- 15 3. A filament of a material capable of absorption, and a coal tar dye impregnating and identifying the same and providing antiseptic qualities.
- 20 4. The combination of a filament and a dye impregnating the same, forming a colored surgical suture providing antiseptic qualities.
- 25 5. The combination with a systematically arranged series of sutures differing in characteristics, of means carried by said sutures for identifying a characteristic of each suture, said means including a plurality of dyes having antiseptic qualities and differing in color, each dye being applied to one of the sutures to render the same antiseptic and impart thereto a characteristic color as compared with the other sutures of the series.
- 30 6. The combination with a systematically arranged series of sutures differing in characteristics, of means carried by said sutures for identifying a characteristic of each suture, said means including a plurality of coal tar dyes having antiseptic qualities dif-

fering in color, each dye being applied to one of the sutures to render the same antiseptic and impart thereto a characteristic color as compared with the other sutures of the series.

7. The combination with a series of surgical sutures differing in absorption period, of means for identifying each suture with regard to the absorption period thereof; said means including a plurality of coal tar dyes having antiseptic qualities and differing in color, each dye being applied only to a suture having a fixed predetermined absorption period, the arrangement being such that the absorption period of each suture in the series is readily distinguishable by the color imparted thereto by the coal tar dye.

8. A package for surgical sutures, including a suture impregnated with an antiseptic dye, and a container therefor bearing a legend, indicating the nature of the suture by reference to the color of the impregnated dye.

9. A package for surgical sutures, including a plurality of inner containers, sutures therein impregnated with characteristically colored dyes having antiseptic qualities, and an outer container bearing a legend, indicating the nature of each suture by reference to the color of the dye impregnated therein.

Signed at New York city, in the county of Kings and State of New York this 17th day of February, A. D. 1920.

CHARLES T. DAVIS.
